(57) **CLAIM**

The ornamental design for a digital-in-wall multifunctional timer, as shown and described.

DESCRIPTION

FIG. 1 is a perspective view of a digital-in-wall multifunctional timer of the subject disclosure;

FIG. 2 is a front view thereof;

FIG. 3 is an open front view thereof;

FIG. 4 is a left side view thereof;

FIG. 5 is a right side view thereof;

FIG. 6 is a top view thereof;

FIG. 7 is a bottom view thereof;

FIG. 8 is a back view thereof;

FIG. 9 is a perspective view of one embodiment digital-in-wall multifunctional timer of the subject disclosure;

FIG. 10 is a front view thereof;

FIG. 11 is an open front view thereof;

FIG. 12 is a left side view thereof;

FIG. 13 is a right side view thereof;

FIG. 14 is a top view thereof;

FIG. 15 is a bottom view thereof; and,

FIG. 16 is a back view thereof.

The broken lines showing are for illustrative purposes only and form no part of the claimed design.
